Primary Examiner — Christian P. McLean*Assistant Examiner* — Adam C Mager(74) *Attorney, Agent, or Firm* — Optimus Patents US, LLC(57) **CLAIM**

The ornamental design for a platform for yachts, as shown and described.

DESCRIPTION

FIG. 1 is a top perspective view of a platform for yachts; FIG. 2 is a top view thereof;

FIG. 3 is a bottom view thereof;

FIG. 4 is a left side view thereof;

FIG. 5 is a right side view thereof;

FIG. 6 is a front side view thereof; and,

FIG. 7 is back side view thereof.

The broken lines are included for the purpose of illustrating portions of the platform for yachts that form no part of the claimed design.
